H. McCloy,

Mop and Brush Holder.

No 21,842.

Patented Oct. 19, 1858.

UNITED STATES PATENT OFFICE.

HENRY McCLAY, OF NILES, MICHIGAN.

COMBINED MOP AND BRUSH.

Specification of Letters Patent No. 21,842, dated October 19, 1858.

To all whom it may concern:

Be it known that I, HENRY McCLAY, of Niles, in the county of Berrien and State of Michigan, have invented a new and useful

5 Implement or Device, to wit: a Combined Mop and Brush; and I do hereby declare that the following is a full, clear, and exact description of the same, reference being had to the annexed drawings, making a part of 10 this specification, in which—

Figure 1, is a side view of my invention. Fig. 2, a side sectional view of ditto. Fig. 3, a front view of ditto.

Similar letters of reference indicate cor- 15 responding parts in the several figures.

This invention consists in having a block or head of triangular form with a handle fitted into it, one side of the head being provided with bristles and forming a brush, 20 and another side being corrugated and having a cloth attached to one end, the cloth and head rendered capable of being so adjusted that the device may be used both as a scrub brush and mop.

25 To enable those skilled in the art to fully understand and construct my invention I will proceed to describe it.

A, represents a triangular or trilateral wooden head or block into one side of which 30 at its center the end of a handle B, is secured by a pivot *a*, the end of the handle being fitted in a slot *b*, in the head or block, as shown clearly in Fig. 2. On another side of the head or block A, bristles *c*, are se- 35 cured forming a brush, the bristles being ar- ranged in the usual way. The remaining side of the block is corrugated or fluted lon- gitudinally as shown at *d*.

C, is a cloth the ends of which are con- 40 nected forming an endless band, the front part of which passes around a rod *e*, at- tached to the head or block at the angle formed by the junction of the corrugated and brush sides of the block or head. The 45 back part of the cloth C, passes through a metal loop *f*, which has a wooden handle *g*,

thereon provided with a ring *g'*, which is fitted on either of two hooks *h*, *i*, secured to the handle B, the hooks being placed one above the other, as shown clearly in Figs. 1 50 and 2.

The implement is used as follows: When the brush side of the head or block A, is to be used, the handle B, is turned so that the brush side is parallel with the floor and the 55 ring *g'*, is placed on the uppermost hook *i*, as shown clearly in Fig. 1. When the parts are in this position the implement may be used equally as well as a brush made for the special purpose. And when the implement 60 is to be used as a mop the handle B, is turned so that the corrugated side of the head will be parallel with the floor and the ring *g'*, is fitted on the lowermost hook *h*, the corrugated side of the head retaining 65 the cloth C, or preventing it from slipping underneath the head. The slot *a*, is made sufficiently wide to allow the handle to adjust itself in a proper relative position with the head or block as the implement is turned 70 for a change of work.

The implement may be cheaply constructed and will prove very efficient for cleaning floors and similar purposes. The cloth C, may when necessary be wrung dry, by sim- 75 ply turning the handle *g*, there being no necessity of touching the cloth C, and thereby wetting the hands. This is an advantage especially in cold weather.

Having thus described my invention what 80 I claim as new and desire to secure by Letters Patent, is,

The trilateral block or head A, attached at one side to the handle B, and having a brush formed on one of the other sides, the 85 remaining side being corrugated and having a cloth C, attached, the whole being ar- ranged as and for the purpose set forth.

HENRY McCLAY.
